UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

ADDRESSING MACHINE.

Application filed October 9, 1922. Serial No. 593,215.

This invention relates to improvements in machines for printing addresses, envelopes, time cards, pay roll lists, etc., the general object being to provide a simple compact and durable machine which is adapted, in successive operations, to receive individual address plates, print from the same, and discharge the plates, the whole being embodied in the comparatively cheap construction, and preferably one which is adapted to be operated by hand.

The machine is of that type wherein there is a bed and mechanism for feeding address plates one after the other along the bed, and a platen carried by an impression arm is adapted to be brought down onto the article to be printed, which is placed face downwardly over the positioned address plate. Means, preferably manually operable, are provided for operating the impression arm and for feeding the address plates from the supply to the impression position and discharging them from such position and providing the ink for the impression.

A prominent feature of the present invention is the provision of an operating arm independent of the impression arm, the impression arm causing a definite pressure of the platen against the address plate and the interposed material irrespective of the amount of force supplied to the operating arm. This is an important point in manually operable machines as it insures a uniform impression.

Another characteristic of my invention is the employment of an adjustable connection between the operating arm and the impression arm for finally regulating the approach of the platen to the work and thereby controlling the depth of the impression to produce work which is light, heavy or medium, as desired.

Another feature of the present invention is the mechanism for positively feeding the plate and for controlling the plate in its various positions to prevent inadvertent displacement thereof and to accurately center it in the printing position.

I prefer to employ as a means of inking, a ribbon adapted to overlie the plate at the impression point and I have provided a simple arrangement for carrying the ribbon and for readily installing or removing it, as well as for feeding the ribbon and for automatically reversing the feed as one

spool becomes full and the other empty. This mechanism is included in my invention.

My invention includes also the mechanism employed for duplicating, that is printing twice in succession from the same address plate, and for indefinitely repeating impression from the same plate, as desired; it includes also a simple and readily operable mechanism for enabling different plates to be brought into action position, as desired.

Another feature of the invention which may be employed is the provision of mechanism for receiving the discharged address plates, storing them in a drawer, removably mounted in a sub-base beneath the machine, such sub-base and storage mechanism being adapted to be associated with a complete addressing machine, whereby the latter may be mounted on the sub-base to effect the automatic storing of the used plates, or may be employed without the sub-base as desired.

Still another feature embodied within my invention, which may be employed if desired, is a suitable listing attachment illustrated and described herein which may be employed to enable the printing of addresses on a continuous strip of paper, as for instance, when making up payroll lists.

Various mechanisms contributing to the operation of the machine and rendering the same efficient in practice are included within my invention and will be apparent from the following description of a preferred embodiment thereof, as illustrated in the accompanying drawings.

In the drawings, Fig. 1 is a front elevation of the machine and sub-base therefor; Fig. 1^a is a side elevation of a plate holding drawer which may be employed and which is shown in the supply magazine in Fig. 1; Fig. 2 is a side elevation showing the sub-base in cross section; Fig. 3 is a plan view of the machine positioned on the sub-base; Fig. 4 is a plan view of the sub-base; Fig. 5 is a cross sectional elevation taken transversely of the machine, substantially along the line 5—5 of Figs. 2 and 3; Fig. 6 is a horizontal section through the base portion of the machine proper in a plane above the operating shaft; Fig. 7 is a vertical transverse section through the base portion of the machine proper; Fig. 8 is a fragment-

tary plan of the forward portion of the bed of the machine; Fig. 9 is a side elevation of the machine without the sub-base; Fig. 10 is a sectional side elevation of the machine in a plane parallel with Fig. 9; Fig. 11 is an enlarged vertical section through the machine; Fig. 12 is a fragmentary vertical section, showing a listing attachment which may be employed and which appears in side elevation in Fig. 9, and Fig. 13 is a sectional elevation through the ratchet operating mechanism of the listing attachment, the relation of Figs. 12 and 13 being indicated by the correspondingly numbered line on the other figure; Fig. 14 (Sheet 9) is a fragmentary cross sectional elevation taken through the bed of the machine and showing the relation of the feed roll of the listing attachment to the bed of the machine. Fig. 15 is a plan of one form of address plate adapted for use in the specific machine shown; Fig. 16 is a detail in vertical section of the reciprocating plate feed mechanism; Fig. 17 is a detail illustrating the adjustment for the depth of impression, being a vertical section on the line 17—17 of Fig. 5; Fig. 18 is a detail of the mechanism for mounting either of the ribbon spools, being an axial section. Fig. 19 is a detail illustrating a dating attachment being a cross section on the line 19—19 of Fig. 8.

The bed of the machine is preferably a low hollow casting, adapted to stand on a suitable support and having a substantially flat top with a central opening from back to front through which the address plates travel, much of the mechanism being mounted within the hollow of such base. More particularly the base casting has horizontal top portions 10 and 11 on opposite sides of an open space 12, approximately vertical edge walls 13 and 14 depending from the outer edges of the top portions and intermediately vertical webs 15 and 16. There is an open space 17, through the side wall 14 and suitable transverse webs 18 and 19 connect the wall 14 with the intermediate web 16. Secured to the top of the bed and covering the most of it are two polished plates 8 and 9 which present a smooth surface along which the paper may be slid to and from printing position.

At the rear of the bed and rising from its upper surface is a magazine in which a supply of address plates is placed for use in the machine. This magazine may be adapted to receive a drawer, of the type shown in my Patent No. 1,448,197, from which a pile of address plates is discharged when the drawer is withdrawn vertically, or it may be a comparatively short casing into which a small number of address plates may be dropped at a time.

When the machine is intended to receive the drawer, the magazine may be of the

form illustrated in Figs. 1, 2 and 5, where there are provided two inwardly facing vertical channel shaped members 20 secured to brackets 21, mounted on the bed. These brackets in this case carry on their inner faces stationary cam blocks 22, which are adapted to coact with retaining springs on the drawer to release the contents when the drawer is shoved downwardly into place. 70

The drawer itself, designated B, is shown in vertical position in the magazine in Fig. 1, wherein the bottom b of the drawer is toward the front, the side walls b¹ extend toward the rear and at the rear of these walls are provided with flanges b². The springs referred to are designated b³, and are secured to the side walls of the drawer. These springs have inwardly projecting ends which are adapted to enter through openings b⁴ in the side walls of the drawer and stand beneath the address plates A in the drawer. The inturned tongues at the lower edges of the springs are bifurcated so that they may straddle the cam blocks 22, whereby these blocks act on the inner side of the springs 30 and serve to withdraw them. The channel shaped members 20 are provided with deeper portions of less width, indicated at 25, to receive these springs. At the upper end these channel bars may be braced by a yoke 26. 95 The same drawer after discharging its contents into the supply magazine may receive the used plates which may be stacked horizontally beneath the addressing machine, as hereinafter described. Fig. 6 shows the drawer in horizontal position inserted to receive such stack. 100

When the drawer is not employed, the supply magazine may readily comprise simply two inwardly facing channels 28, Figs. 10 and 11, these channels being flanged at their lower ends and thereby secured to the bed in place of the brackets 21. 105

The address plate may be of any suitable form. Thus it may be of a type illustrated in Fig. 15 and shown more fully in my design application No. 1109, filed Mar. 10, 1922, and comprise a sheet metal member A, having tubular edge portions a, and having intermediately parallel rows of buttons or projections a¹, struck up from it and adapted to carry under-flanged embossed strips a². This construction, however, is cited only as an illustration, as various types of printing plates or address holding members may be employed. 115

When the plates are in the supply magazine, the bottommost plate rests on a pair of horizontal rails 40, which extend lengthwise of the machine within the central opening 12, substantially at the top thereof and a short distance beneath the cover plates 18 and 9. These rails are secured to and supported by cross webs 14 of the frame at the rear and intermediately by a cross portion 125 130

42 of the frame and at the front by projections 44 extending inwardly from the webs 15 and 16. These rails provide a slideway along which the plates are fed toward the front of the machine past the printing position and ultimately discharged. The plates are properly positioned laterally in the magazine before they descend onto the rails by a channel shaped member 27, secured to the back of the magazine and having inwardly inclined tongues 29 (Figs. 3 and 5) adapted to engage between extensions of the tubular end portions *a* of the address plate.

15 In the particular embodiment illustrated, there are four address plates in a row on the rails 40 during active operation; that is, to say, one plate at the base of the stack, a second plate intermediate the stack and the printing position, a third plate at the printing position, and a fourth plate in front of the printing position and ready for discharge when the line of the plates is moved forward one step. This number of active plates is convenient, but may be varied, if desired.

30 The printing position for the plates, as shown in Fig. 11, is the second position in front of the stack, where the plate is directly over and rests on the stationary horizontal frame portion 42. At this point, the plate lies beneath a transverse inking ribbon 50 and also beneath a platen 60 provided on an impression arm 70, all to be hereinafter more fully described. A card, envelope or other material to be printed is placed on top of the ribbon and the impression arm brought down to effect the impression. Then the impression arm rises and the plate is fed to the fourth position shown in Fig. 11, where it remains until the next operation when it is discharged into a receiving opening in front of the machine between suitable frame extensions 48 and 49, to be hereinafter described.

45 I will now describe the means for feeding the plates one after the other from the bottom of the stack to the discharge point at the front of the machine. The feeding mechanism includes a pair of parallel reciprocating longitudinal bars 80 standing on edge and carrying pawls 85 pivoted to them and pressed upwardly to engage the plates. These bars are supported and guided near the front in notches made through the transverse frame member 42, and at their rear rest on flanged wheels 83 which are loosely journaled on a transverse shaft 100, hereinafter referred to.

60 Each of the pawls 85 is provided on its under side with a downwardly extending ear 86 which is nearly circular and connected with the pawl by a narrow neck, and occupies a correspondingly shaped recess formed in the upper edge of the bar 80.

The pawl is prevented from displacement by two collars 87 held to the sides of the pawl after it is placed on the bar by a through rivet pin 88. A detail of this pawl and its cooperating parts is shown in Fig. 16. The pawls are pressed upwardly by springs 89, seated in recesses in the upper edge of the bar and in the under face of the pawl respectively, the position being limited by a tail 84 on the pawl, engaging the upper edge of the bar. These pawls lie between the rails 40 and the frame webs 15 or 16 and serve to engage the rear end of the tubular portion *a* of the address plate.

15 The reciprocating bars 80 may be moved forwardly to feed the address plates by the following mechanism. The two bars are connected by a yoke 90 pivoted to the bars at the rear end of the yoke. The forward end of the yoke is pivoted to the upper end of a second yoke 91, which at its lower end is pivoted to the frame members 15 and 16. The yoke 91 has a cross bar 93 which is normally engaged by a link 95 (shown disengaged in Fig. 11) the rear end of which is pivoted to a rock arm 96 pinned on the shaft 100, heretofore mentioned. On the outer end of this shaft is keyed a hand lever 102, carrying at its end a suitable handle 103. When this handle is drawn forwardly and downwardly (assuming that the link 95 engages the rod 93), the feed bars are thereby moved forward, and on the return stroke of the operating lever the bars are returned. A screw 99 carried by the frame member 41 serves to adjustably limit the rearward stroke of the feeding mechanism, and a spring 98 attached to the frame and to the rod 93 insures such return.

20 The feed bars are provided near their rear ends with upwardly extending portions 110 which rise to a sufficient height to come behind the bottommost plate in the stack, and when these bars are fed forward, the front edge 111 of these extensions engage the rear ends of the tubular portions *a* of the bottommost plate, and shove it out of the stack, while the top edges of the extensions support the rest of the plates in the stack. At the completion of the stroke, this advanced plate 115 has been carried beneath the cover plate 9 to a point intermediate of the stack and the printing position, where it is adapted to be engaged by the rearmost pawl 85 on the next forward stroke.

25 It will be seen from the mechanism described that successive operations of the handle 103 may feed the plates one after the other forwardly from the stack to the intermediate position, then to the printing position and finally to the discharging position. In this operation, the plates travel over certain detent springs 120, which are secured to the rails 40 and have V-shaped noses extending upwardly through openings 121 in the 130

rails 40. As shown, more particularly in Fig. 14, these V-shaped noses engage the successive grooves a^3 in the underside of the address plate and thus prevent their being jarred out of position or carried too far by momentum and also accurately center them in the printing position.

The impression arm 70 heretofore referred to, which carries the platen 60 is pivoted to brackets rising from the bed. As shown, this impression arm is bifurcated and has two rearwardly extending arm portions 71 and 72 formed to stand on opposite sides of the magazine. The portion 71 is journaled on a stud 73 carried by brackets 74 and 75, while the portion 72 is journaled to a stud 76 carried by a bracket 77. The arm 71 extends beyond the pivot 73 in the form of an arm 78 which carries a roller 130. This roller coacts with a cam 140 on the main shaft 100.

When the operating lever 102 is drawn forwardly, the cam 140 swings the impression arm to carry the platen 60 downwardly to make the impression. The cam has a surface of increasing radius sufficient to carry the platen into impression action before the operating arm has completed its stroke, and then the cam is purely concentric for the rest of its active surface, so that the slight rest of the platen while impressing is not accompanied by increased pressure. The roller 130 is maintained in snug engagement with the cam at all times by the spring 145 anchored at its lower end to the frame and its upper end to an arm 146 integral with the arm 72. Suitable stops are provided for limiting the movement of the operating means shown in Figs. 5, 9 and 10 as comprising shoulders 147 and 148, and a stationary abutment 149 with regard to the frame.

It results from the above construction that whenever the operating arm 102 is drawn forwardly the amount of its stroke, the platen is brought down to a definite point irrespective of the force applied to the operating arm. This causes uniform impression to be given, notwithstanding variations in manual operation, and is an important feature of this invention.

To vary the depth of impression so that the same inking ribbon may readily produce printing which is "light", "heavy" or "medium", as desired, I adjust the position of the cam roller 130 in the arm 78. To effect this, I mount this roller on an eccentric 131 and I provide suitable means for turning the eccentric and holding it in adjusted position. As shown in Figs. 5 and 17, the eccentric carries an arm 134 which has an arcuate edge provided with worm teeth 135, and on the arm is suitably journaled a worm 136 meshing with these teeth and having a knurled operating knob 137. By this means, I can adjust to a nicety the impression be-

tween the platen and plate and retain the adjustment as long as desired, the worm construction being self locking.

It is desirable to provide interchangeable platen surfaces of varying extent to enable efficient printing from addresses of different numbers of lines and to enable the omission of the salutation where the address plates carry such salutation. To provide for this and also to enable the platen to be accurately positioned, with reference to the address plate, I provide the mechanism best shown in Figs. 2, 7, 10 and 11, which will now be described.

The forward portion of the impression arm comprises two arm members 70 terminating in a cross plate 150; beneath this is a U-shaped stirrup 151 carrying the platen 60 and secured to the cross plate 150 by a supporting screw 153 and suitable clamping screws 154 and 155. By loosening the clamping screw 154 for instance, and tightening the screws 155, the platen may be swung slightly forward, and by the reverse operation swung slightly rearward, and these screws also furnish means for tipping the platen laterally to cause the underface of the platen to be strictly horizontal when it is in impressing engagement.

The platen member 60 is shown as a hollow box-like member of U-shaped section having web portions 160 and 161 keyed on a rod 163, which is journaled in the depending portions 157 of the stirrup 151. The platen is held normally in the position shown in Figs. 2 and 11, by reason of a squared portion 165 on the web 161 engaging a rib 158 on the stirrup. A spring 166 surrounding the shaft 163 and compressed between the web 161 and the stirrup 157, normally maintains the platen in this position. If, however, it be shoved to the right in Fig. 7 a rounded portion 167 of the web 161 comes under the rib 158 and then the platen may be turned in either direction 90° , to bring either of its other faces, into position for action. A suitable knob 170 on the shaft 163 furnishes means for shoving it endwise and turning it. The endwise movement is limited by the hub of the knob engaging the stirrup 157, and rotation in this position is limited by lugs 171 on a hub engaging one side or the other of the rib 159 on the stirrup.

By having the pads on the opposite sides of the platen surface of less transverse extent than the normal pad (as indicated at 168 and 169 in Fig. 11), I may readily eliminate the salutation, which may be carried by the address plate, or may eliminate if desired the address other than the name or such other material as desirable, by simply turning the platen to one side or the other.

It is sometimes desirable to print a date or other added matter which is not on the address plate. To provide for this, I make a suitable dovetail in the frame portion 173, 130

Fig. 7, and I slide into this a holder 176, Fig. 19, which may have undercut projections 176 adapted to carry one or more printing strips 177. Such device stands at the side of the plate in printing position and lies beneath the inking ribbon, and the paper is impressed against it by a pad 178 on the extended portion of the platen, which houses the spring 166 heretofore mentioned. The member 176 which carries this permanent printing surface may conveniently be curled over at its edge as shown at 179, Fig. 7, which forms a convenient sliding support for the ribbon and also provides ready means for drawing out the spring holder.

I have referred to the inking ribbon 50 extending across the address plate which is above the frame member 42. The arrangement of ribbon spools and the mechanism for mounting them, and for feeding the ribbon step by step succeeding each impression, and for reversing the direction of feed when a spool becomes empty is best shown in Figs. 6, 7, 8 and 18, and will now be described.

The ends of the ribbon are mounted on a pair of spools which are held one above the other, in the frame opening 17 between the transverse web members 18 and 19. These spools are clamped between two pairs of heads, each of which pairs is provided with a ratchet adapted to enable the driving of that spool. More specifically, I mount in the web 19 a pair of stationary horizontal studs 181 and 180. On each of these studs is a ratchet wheel 182 and 183, respectively, loosely mounted on the stud. Connected with the ratchet wheels is a disk as 185, with a stud projecting through it and having a head beyond it. The head of the stud is adapted to receive the opening of the ribbon spool with the disk 185 bearing against the flange of the spool. The spools are suitably locked to the ratchet wheel disks 185 to enable their ready driving thereby, as for instance by projections 193 on the spool flange engaging openings 194 in the ratchet disk as shown in Fig. 18.

Directly opposite the studs 180 and 181 are a pair of rods 186 and 187 mounted in the front of the frame and the cross web 18 and carrying disks 188 and projecting central portions beyond the disks. The spools are mounted between the front and rear disks and so maintained by springs 189 pressing the rods 186, 187 rearwardly. These rods may be drawn to the front by knobs 190 and 191 to free the spools.

When the spools are mounted between the disks as explained, the ribbon passes from the upper spool intermediately across the top of the bed over the adjacent portions of the top plates 8 and 9, and over the address plate which is in printing position (where the top plates are cut away) and then down the outer side of the exterior wall 13 of the

bed, which in this region is inset as shown at 195 to protect the ribbon, and thence passes under the frame of the machine and back to the lower spool. To guide the ribbon where it passes downwardly on the outside frame, I may mount within the inset portion 195 a plate 197 having at its edges vertical guiding projections 198, as shown in Figs. 2 and 6.

Due to the mounting described, both ribbon spools and the ribbon may be entirely removed from the machine whenever desired and no threading of the ribbon is necessary, which avoids any necessity for taking the ribbon off the spools. The simple act of pulling out the knobs 190 and 191 frees the spools so that both the spools and the ribbon may be removed, and fresh pair of spools and ribbon put in their place.

To feed the ribbon periodically during the operation, as well as to automatically reverse it when either spool becomes empty, I provide the following simple mechanism. Referring to Figs. 6 and 7, 200 designates a rod mounted in the frame portions 18 and 19. On this rod is journaled a bar 201 having a slotted end 202, in which is mounted a pin 203 carried by an arm link 204, the other end of which is pivoted at 205 to a rock arm 206 on a shaft 207, and also pivoted at 205 to a link 208 which carries a pin 209 adapted to engage the teeth of either ratchet wheel 182 or 183. A tension spring 210 connects the pins 203 and 209. The shaft 207 carries at its other end a rock arm 212 carrying a roller 213 engaging the crown cam 214 on the main shaft 100. This cam is positioned to cause a movement of the arm 206 toward the right in Fig. 7, when the operating arm is drawn forwardly. This movement carries the pin 209 toward the right into engagement with a new tooth of the ratchet wheel, stretching the spring 210, then as the operating arm is returned and the rock arm 206 swings in the opposite direction, the spring 210 retracts the pin 209, thus feeding the ratchet engaged by that pin and correspondingly turning the ribbon spool. Thus following each impression, the ribbon is given a slight movement to present a fresh face for printing.

To cause the pin 209 to automatically shift from a full spool to an empty one, I mount on the arm 201, a roller 216 which is adapted to lie against the body of the ribbon wound upon the spool. As such wound portion increases in diameter, this roller gradually swings the arm 201 away from such spool and as the spool becomes filled, the arm has swung far enough to straighten the toggle provided by the two links 204 and 208, and then as more ribbon is wound on the toggle swings over into the opposite direction, as shown in dotted lines in Fig. 7, wherein the pin 209 engages the other ratchet wheel, as

183, after which the same movement of the operating lever feeds that wheel and the ribbon travels in the reverse direction. The slot 202 enables the movement of the links 5 during the straight condition of the toggle.

To insure the mechanism described snapping quickly from one spool to the other, I provide a spring pressed plunger 220, mounted in a casing 221, rigidly secured to the 10 shaft 200. This plunger is pressed outwardly by a spring 223. It has a V-shaped nose adapted to engage either of two surfaces on a V-shaped lug 225 on the bar 201. During the gradual swinging of this bar 15 201, as the spool winds up, this lug cams the plunger inwardly until the point of the lug engages the point of the plunger, after which the reaction of the plunger tends to force the arm into position to cause engagement 20 with the other ratchet.

It is frequently desirable to set the machine so that instead of feeding an address plate for each impression, it feeds one only for every other impression, thus allowing 25 duplicate imprints from each plate and for other work it is desirable to allow the address plate to remain at the impression place for as many strokes as desirable to enable an unlimited number of impressions to be 30 made. I have provided simple mechanism for readily accomplishing this which I will now describe with particular references to Figs. 6 and 11.

Mounted in the frame webs 16 and 17 is a 35 transverse shaft 230 on the outer end of which is a ratchet wheel 231 having an even number of teeth, preferably six, as shown in Fig. 10. Cooperating with this ratchet wheel is a pawl 232 on an arm 233 on the 40 shaft. This arm is connected by a link 234 with a rock arm 235 on the main shaft 100. I also utilize this arm 235 for the attachment of the main spring 238 for returning the operating arm 102.

The mechanism described gives the ratchet wheel 231 a fraction of a turn (e. g. 1/6) for each operation of the machine. This ratchet wheel is pinned to the shaft 230 to which is pinned a polygonal member 240 having half as many faces as the 50 number of teeth on the wheel 231. In this instance this member is a triangular block. This block bears against an arm 241 which is pivoted on a rod 242 which is tightly mounted in a pair of arms 243 journaled on the shaft 230. The arm 241 extends rearwardly in the form of a rigid extension 245 which has an upturned end 246 adapted to engage the link 95 connected to the arm 96 on the main shaft 100. A spring 247 tends to maintain this engagement. The rod 243 is bent at right angles and extends forwardly, as at 250, through a slot 251 in the frame and is provided with an operating knob 252. A pin 253 extends through the

rod in front of the frame and coacts with a pivoted latch bar 255 which is drawn rearwardly by a spring 256. There are three notches in this latch bar, as shown in Fig. 11, adapted to hold the rod 243 in 70 either the intermediate position shown in Fig. 11 or a position above it or one below it.

The mechanism described, giving the shaft 230 one sixth of a turn for each operation, while the block 240 has only three sides, results in turning that block into the position shown in Fig. 11, on every other stroke, while intermediately the point of the triangular block is engaging the arm 241 and thereby holding it down. The position shown in Fig. 11 is the position for duplicating and on the stroke represented in this figure, the extension 245 holds the arm 95 out of engagement with the rod 93 so that no feeding of the plates takes place. On the next stroke, however, one of the points of the triangular block 240 engages the arm 241 and thus lowers the upturned end 246 causing the link 95 to engage the rod 93, so that on that stroke the operation 90 of the lever 102 feeds a plate. Accordingly the plates are fed with this setting for every other stroke.

What may be called the normal setting of the machine—where the plate is to be fed for each impression—is where the pin 253 of the setting rod is in engagement with the uppermost notch 258 of the latch 255. In this case the upturned end 246 of the member 245 is lowered to such an extent that it 100 cannot engage the link 95, whatever the position of the block 240. Accordingly the operation of the triangular block is entirely idle and the link 95 remains continuously connected with the feeding linkage. 105

For a continuous printing from one plate, it is only necessary to lower the knob 252 to its lowermost position, where the pin 253 engages the notch 259. In this case the upturned end of the member 245 raises the link 95 so high that it cannot engage the rod 93 even when the triangular block 240 lowers the member 245. Accordingly the operation of that block is again idle and the plate feeding mechanism remains continuously disconnected from the operating shaft, enabling as many prints as desired to be made from the single plate. It will thus be seen that by this very simple mechanism, I am enabled to obtain normal operation, duplicating or the continuous printing from one plate as desired. 110 115 120 125

I will now describe the restacking of the plates after the imprints have been made. Fig. 11 shows an address plate standing beneath the top plate 8 of the machine and in front of the address plate, which is receiving the impression. On the next stroke this forward address plate is advanced off of the rails 40 over the open space between the 130

frame extensions 48 and 49, heretofore mentioned and drops by gravity. When the manual transference of a few plates at a time to the storage drawer is intended, I 5 place on the inner face of these frame parts 48 and 49 sheet metal liners 260 which have inwardly projecting flanges 51 at their lower edges. The delivered plates drop by gravity the lowermost plate resting on these 10 flanges and each surmounting plate resting on the plate below it. In such ejection, the plate is prevented from being carried by momentum out of this guideway by the upwardly extending frame flange 263 formed 15 on the inner face of the frame portions 48 and 49.

When a reasonable number of plates have accumulated in the guideway the operator 20 grasps them between his thumb and fingers extending through the open front of the machine and lifts them above the guideway and replaces them in a storage receptacle. To prevent jamming if the restacker magazine becomes entirely filled, I incline the 25 flanges 260 slightly toward the front of the machine, as shown in Fig. 11, with the result that the successive plates are similarly inclined so that when the stack is filled, the topmost plate will lie at its front edge 30 above the frame flanges 263 and thus the next plate delivered would simply shove this topmost plate out of the machine. No harm would be done and the operator's attention would be called to the fact that the 35 stack was filled.

The machine described is complete in itself to effectively accomplish address printing. Instead, however, of placing comparatively few plates at a time in the receiving 40 magazine and removing a like number from the restacking device, I provide means, as already described, for supporting an entire drawer of plates in place of the short supply magazine. I also contemplate providing a sub-base for the machine which is equipped 45 with means for horizontally stacking the delivered plates and is adapted to receive such drawer after its contents have been discharged into the supply magazine. The sub-base is so arranged that the delivered and 50 stacked plates will pass directly into the drawer upon its insertion in the sub-base, thus avoiding the necessity of removing a comparatively few at a time from the machine. I have made this sub-base entirely 55 detachable from the main machine and still cooperating with it, so that it may be supplied either with the machine or supplied later to the users who already have the addressing machine.

I will now describe the sub-base with particular reference to Figs. 1, 2, 3 and 5. The frame of the sub-base comprises a hollow casting having walls which for the most part align with the walls of the addressing ma-

chine. That is to say, the sub-base has side walls 280 and 281 aligning with the machine walls 13 and 14. It also has front portions 282 aligning with the machine front and rear portions 283 aligning with the outer 70 parts of the rear portion, while adjacent the center the sub-base extends in front of the extension members 48 and 49 of the frame and at the rear extends behind the rear wall of the frame, as shown at 285. Intermediately, the side walls of the sub-base are braced by cross members 287 and 288. The front of the sub-base is open so that, after the plates have accumulated therein, the open ended drawer may be inserted horizontally into the sub-base and thus receive the stacked plates, after which the drawer may be withdrawn having plates within it.

Within the opening in the front of the sub-base is rigidly secured an open frame 290. Extending rearwardly from this frame are two angle bars 291 which rest on the cross bars 287 and 288. Resting on the horizontal flange of these angle bars are two flat strips 293, the rear ends of which are shown as curved around a stationary rod 294. Extending across the top of the sub-base is a horizontal bar 296 which carries an upwardly extending curved deflector 297 adapted to extend between the frame extensions 48 and 49 of the addressing machine. Now when a plate is delivered at the top of the space between these extensions it falls downwardly and by reason of the deflector assumes a vertical position and drops onto the forward end portion of the strips 293 between the vertical flanges of the angle bars 291, as shown at A in Fig. 2.

In the position mentioned (Fig. 2) the address plate rests against an inclined gate 300. This gate is pivoted at its upper corner 301 to an open rocking packer frame 302 which is pivoted at its lower edge by means of pins 304 to the sub-base side members. The upper end of the rocking frame 302 is connected by a pair of links 305 with a pair of arms 306 on the main shaft 100, the connection providing for loose play by means of slots 307 in the links. The portions of the arms 306 connected with the links are 110 readily detachable from the portions connected with the rock shaft 100, enabling the ready separation when the sub-base is not employed. To effect this, I make the connection by flanges 308, the lower portion of 115 the arm through which screws 309 pass into the upper portion of the arm. When the sub-base is not used these upper portions are simply idle.

The operation of the packing mechanism 120 described tips the foremost plate A which has inclined toward the front until it inclines toward the rear, where it rests against a suitable follower 310 or against the other plates already against the follower. This 125

follower is supported on a stationary bar 312 which is supported at its forward end by the cross member 296 and at its rear end by being secured to the rear wall 314 of the sub-base frame. As the plates are discharged one after the other into the sub-base the rocking follower causes the supply with the follower to gradually travel backward so that eventually plates sufficient to fill an entire drawer may be accumulated in the sub-base.

As heretofore stated, the sub-base is adapted to have the drawer shoved into it to receive the supply of plates. When this is to take place the hinged gate 300 is swung upwardly on its pivot 301 as shown in full lines in Fig. 4 and in dotted lines in Fig. 2. Then the drawer is shoved rearwardly through the open member 290, the drawer being indicated at B in Fig. 4. This drawer as heretofore stated has a bottom plate b^1 and side walls b^2 with turned-over top flanges b^3 . The drawer also has plate retaining springs b^4 on its sides which have inturned ends, which, when the drawer is idle, stand behind openings b^5 in the side wall of the drawer. When the drawer is pushed into the sub-base, its bottom plate passes under the supporting strips 293, the forward edge of which is slightly beveled (Fig. 2) to lift it upon such insertion. The side walls of the drawer pass outside of the ends of the plates which have been inserted, the plates being held centrally by reason of the strips 293 engaging slightly recess bottom portions of the plate, as shown in Fig. 5. As the drawer comes into its rearmost position, the inturned ends of the springs b^4 abut adjustable stops 320 carried by a cross web 322 of the sub-base frame, whereby those spring ends are brought into registration with the openings b^5 in the drawer walls and these ends then spring into the interior of the drawer through these openings and stand behind the rearmost plate and alongside of the end of the follower 310 which is narrower than the width of the plate. At the same time a hole b^6 in the bottom of the drawer comes beneath the nose of a gravity pawl 325 (Fig. 2) carried by the follower and this nose drops into the opening.

When the drawer is drawn out, the follower and plates travel with it until the follower is brought back to its original position when the nose of the pawl 325 rides up on a spring 326 carried by the cross frame member 287 which frees the follower. Then the drawer is removed the rest of the way with its load, the follower being left in starting position. Then the gate 300 is turned down into the position shown in full lines in Fig. 2 and the restacker is ready to receive another load of plates.

Before attaching the sub-base the lower ribbon spool is removed from its mounting,

and the ribbon, instead of passing directly across the bottom of the main base, is then passed downwardly beneath the sub-base and beneath the restacker and then the spool mounted in position, the course of the ribbon being indicated at 50 in Fig. 5. The sub-base wall 280 has guides 330 for directing the ribbon whence it passes inwardly beneath the restacker, and as it turns diagonally upwardly it is guided by one of the angle bars 291.

It is frequently desirable to print addresses on a continuous strip of paper, as, for instance, when making a payroll list, instead of on individual cards. To provide for this, I furnish a simple listing attachment which is best shown in Figs. 3, 9 and 10, 12 and 13. This listing attachment comprises a bracket 340 adapted to be secured to the side walls 13 of the main frame and carrying in suitable bearings 341 and 342, a shaft 344. This shaft has pinned to its inner end, a knurled or other-wise surfaced feeding roller 345 adapted to engage the strip of paper. The outer portion of the shaft is connected by a suitable ratchet mechanism with the main operating shaft 100, whereby the roller may be automatically rotated, its lower surface traveling toward the rear, to feed the paper periodically. Coacting with the roller 345 is a spring plate 346 mounted beneath the roller and having its ends sprung into openings 347 in the top plate 9 of the machine. The strip to be printed, designated C in Fig. 12, lies between the spring plate and the listing roller 345.

I have provided a friction ratchet clutch, best illustrated in Figs. 12 and 13, in the connection between the operating shaft 100 and the lister shaft 344. That is to say, pinned to the shaft 344 is a ratchet wheel 350 which is embraced by the built-up hub 351 and 352 of an arm 353, and balls 354, pressed by springs 355, form the engaging means between the ratchet wheel and arm, as will be well understood. The arm 353 is connected by a link 357 with the rock arm 358 on the shaft 100; a slot 359 in the link providing loose play. A spring 360 anchored to the bracket 340 and to the arm 353 tends to turn the arm in the idle direction.

It results from the above described mechanism that as the main operating arm is drawn forwardly to effect an impression the spring 360 carries the ratchet arm 353 idly toward the front. Now as the operating arm returns the first portion of its movement does not effect the lister roller 345 because the pin on the arm 358 is traveling in the slot 359, but when the pin engages the right hand end of that slot (Fig. 13) the further movement rocks the arm 353 and through the ratchet connection turns the roller 345. The amount of this effective movement is such as to feed the strip toward the rear.

a distance corresponding to the region covered by the addresses.

The amount of the effective stroke of the listing attachment may be varied to bring it in harmony with the space occupied by the addresses by adjusting a stop block 362 slidably mounted on a rod 363 carried by the bracket 340; this block being locked in adjusted position by a set screw 365. The 10 block limits the forward movement of the arm and hence controls the amount of feed caused by the rearward movement thereof.

The listing attachment preferably carries suitable guides for the strip of paper C to 15 be printed. As shown, these guides comprise angle members 370 carried by rods 371 slidably mounted in the bracket 340 and clamped by set screws 373. These angle members are adapted to engage the right hand edge of the strip.

For printing of cards or envelopes, when the listing attachment is not employed, I prefer to mount suitable gages for positioning the rear edges of the member to be printed. 25 These gages may conveniently comprise blocks 380 on the forward ends of rods 381 slidable in the frame ears 75 and 77 and locked by set screws 382. The cards or envelopes are prevented from hitting the edge 30 of the ribbon 50 when they are put in place by means of a wire 385 fastened to the top plate 8 and overlapping the ribbon, as shown in Fig. 8.

From the foregoing description, it will be 35 understood that a machine embodying my invention may be constructed comparatively cheaply, is simple to operate, and capable of a wide variety of uses. If it is desired to avoid the expense of the mechanism for 40 restacking a drawer full of address plates, it is very easy to place in the supply magazine as many plates at a time as the operator can conveniently grasp in one hand and simply remove such plates from the front of 45 the machine after they have been used. Assuming that the machine is thus arranged and that the operator desires to print on cards or envelopes, he sets the adjustable back gage to properly position the imprint 50 the desired distance from the top edge of the card or envelope and then ordinarily with his left hand, feeds such cards, one at a time into position, and with his right hand manipulates the operating lever. If 55 the imprint is too light or too heavy, he adjusts the cam roller accordingly and thereafter no further adjustment is necessary, until the gradual depletion of the ink in the ribbon requires a heavier impression.

60 If on the other hand, the operator desires to print the addresses on a continuous strip of paper, he simply removes the back gage and installs a listing attachment and properly adjusts the latter to feed the paper the 65 desired distance following each impression.

The strip of paper curls up in the receiving holder and at the end of the operation may be drawn out to one side.

If the sub-base is employed, the only changes necessary are to substitute a drawer 70 holder for the short supply magazine, place the deflector in front of the machine and in place of the spools for the different plates, remove the lower ribbon spool, attach the packer operating arms of the sub-base to the 75 corresponding arms of the addressing machine and pass the lower ribbon spool beneath the sub-base and reposition it in the addressing machine. When so arranged the entire drawer of address plates is placed in 80 the supply magazine holder and the drawer may conveniently be left standing in that position until it becomes empty. Then when all the plates have been restacked in the base, it is only necessary to lift out the 85 drawer from the supply magazine and insert it horizontally in the sub-base and draw it out with its load of used plates. The machine is then ready for the insertion of a new set.

90 I claim:

1. In an addressing machine, the combination of means for feeding address plates, an impression platen, an operating lever, mechanism connecting the lever with the 95 plate feeding means, and a cam connection between the lever and the platen adapted to move the platen to a definite position irrespective of the force applied to the lever.

2. In an addressing machine, the combination of means for feeding address plates, 100 an impression arm, a platen carried thereby, an operating handle, mechanism connecting the handle with the plate feeding means, and a cam connection between the handle 105 and impression arm adapted to swing the impression arm to a definite position irrespective of the force applied to the handle.

3. In an addressing machine the combination of an impression arm, a platen carried thereby, a shaft, a hand lever for turning the shaft, a cam on the shaft adapted 110 to coact with a roller on the impression arm, said cam having its surface of greatest radius concentric with the shaft whereby the 115 platen is moved to a definite plane, and stops for limiting the movement of the hand lever independently of the cam.

4. In an addressing machine, the combination of means for feeding address plates, 120 a shaft, mechanism connecting the shaft with the feeding mechanism, a cam on the shaft, an impression arm, a roller carried by the impression arm and coacting with the cam, and a hand lever on the shaft.

5. In an addressing machine, the combination of a shaft, a hand lever thereon for operating, a cam on the shaft, a platen, a pivoted arm carrying the platen, a roller connected with the arm and coacting with the 125 130

cam, an eccentric mounting for the roller, a worm and worm sector for turning such mounting and locking it in adjusted position.

6. In an addressing machine, the combination with means for feeding address plates, of a ribbon beneath which they may be fed, a platen, an impression arm carrying the platen above the ribbon, a main shaft, a connection between the same and the plate feeding mechanism, a cam on the main shaft, a roller connected with the impression arm and coacting with the cam, and means for adjusting the roller to vary the depth of impression.

15 7. The combination with a set of address plates, each formed with upwardly extending corrugations providing transverse grooves on its underside, laterally extending lips at the tops of said corrugations and 20 printing strips overlying the corrugations and retained by said lips, of means for feeding the address plates, and a spring detent adapted to enter one of said grooves and hold the plate against inadvertent displacement.

25 8. In an addressing machine, the combination of means for holding a stack of address plates, of means for feeding the plates from the bottom of the stack, including a reciprocating bar which is arranged to support the 30 stack above the bottom plate as the bottom plate is fed.

9. In an addressing machine, the combination with means to support the stack of plates, of means including a reciprocating 35 bar for feeding the bottommost plate out of the stack, said bar having a raised portion extending for the larger portion of the distance across the plate and thus adapted to support the stack above the bottom plate

40 as the bottom plate is being fed forward.

10. In the plate feeding mechanism of an address printing machine, the combination of a reciprocating feed bar having a notched edge and a pawl having a tongue movably 45 occupying the notch and a spring between the edge of the bar and pawl.

11. In a plate feeding mechanism for address printing machines, the combination of a reciprocating bar having in its edge a 50 notch which is partially circular, and a pawl having a tongue which is substantially circular with a narrow neck and which occupies said notch, whereby the pawl is pivoted to the edge of the bar, and means for 55 preventing the pawl passing edgewise out of the bar.

12. In an addressing machine, the combination with means for feeding address plates of an inking ribbon passing transversely 60 across the address plate at the impression position, passing to a position beyond the side edge of the frame of the machine and thence down the outside of the machine and backwardly into the machine beneath the 65 positioned address plate, spools within the

machine carrying the wound up ends of the ribbon, and means for feeding one of said spools.

13. In an addressing machine, the combination with a frame, of means for feeding plates along the same, an impression platen adapted to coact with the plates and an inking ribbon passing transversely over the plate beneath the impression platen, and down the outer side of the frame and beneath the frame, and projections on the edge of the frame for guiding the ribbon, the space between the projections being open outwardly to allow installation of the ribbon without threading.

14. In an addressing machine, the combination with a frame, a pair of top plates thereon notched at their edges to provide an impression space and slightly separated to provide for installation of a ribbon, and an inking ribbon mounted at one end beneath the plates and passing across the space between the plates and downwardly and backwardly beneath the impression position, and spools carrying the ends of the ribbon.

15. The combination of reciprocatory plate feeding mechanism including a reciprocating bar, a manual lever, connecting linkage between the lever and bar, one of the links being raisable from its point of connection, a seating lever adapted to engage the link and raise it from its lowermost position to either of two elevated positions, means for lowering the engaging end of said seating lever on every other stroke whereby said linkage becomes reengaged on every alternate stroke or remains continuously out of connection dependent upon the position of the seating lever.

16. In an address printing machine, the combination of an impression arm, a platen carried thereby and having a plurality of impressing faces, means for holding said platen with any face in active position, and means whereby such holding is released on longitudinal movement of the platen.

17. In an address printing machine, the combination of an impression arm, a platen having a plurality of faces carried by the arm, said platen being mounted on a shiftable shaft held on a fixed axis, means for locking the platen in one longitudinal position of the shaft and releasing it in another longitudinal position.

18. In an addressing machine, the combination of an addressing arm, a platen holder carried thereby, a platen having a plurality of faces mounted in said holder and longitudinally shiftable therein, a spring tending to shove the platen longitudinally, a locking device to hold the platen in fixed position normally under the influence of the spring, and means for shoving the platen longitudinally to release the lock and for turning it when released.

19. In an address printing machine, the combination of an impression arm, a platen holder carried thereby, a platen shaft slidably mounted in the platen holder, a platen 5 rigid on the shaft, there being round and polygonal portions concentric of the shaft, and means on the platen holder adapted to engage either of said portions according to the longitudinal position of the platen, 10 whereby by shoving it lengthwise it may be released and turned.
20. In an address printing machine, the combination of a platen carrier, a platen having a plurality of faces, means for locking the platen in normal position, means for shoving it longitudinally to release the lock whereby the platen may be turned, and engageable lugs adapted to limit the turning 15 of the platen.
21. In an address printing machine, the combination of a platen carrier, a platen having a plurality of faces, means for locking the platen in normal position, means for shoving it longitudinally to release the lock 20 whereby the platen may be turned engageable lugs adapted to limit the turning of the platen, and a spring housed within the platen and bearing against the platen carrier and tending to return the platen to lock position.
22. In a restacking mechanism for address printing machines the combination with a frame of a supporting strip for the plates, said strip being supported at one 25 end and free at the other end, and means for guiding an open ended drawer beneath said strip.
23. The combination with an address printing machine of a restacking device 30 comprising a supporting strip for plates, a follower adapted to support the plates while they rest on edge on the supporting strip and a packer adapted to shove the plates and follower to cause them to travel along the strip combined with an open ended drawer which may be inserted with its bottom beneath the strip and its side walls beyond 35 the ends of the follower.
24. The combination with an address printing machine of a sub-base having restacking means including a follower, a drawer adapted to be inserted in the sub-base to receive the stacked plates, and means whereby the withdrawal of the drawer returns the follower to initial position.
25. The combination with an address printing machine adapted to deliver used plates forwardly and downwardly, of a sub-base 40 adapted to be mounted beneath the address printing machine and adapted to receive plates and stack them in a horizontal row toward the rear, a supporting strip for the plates so stacked, a follower for the plates, the sub-base having an opening at the front through which an open ended drawer 45
- may be inserted with its bottom beneath the support strip and with its sides beyond the ends of the follower, and means whereby the withdrawal of the drawer withdraws the plates and follower to a certain position, and means for then releasing the follower. 50
26. The combination with an address printing machine of a restacking base therefore, a packer and a follower in said base, said follower being provided with a latch, a drawer adapted to be inserted in the sub-base and having means which the latch engages whereby the withdrawal of the drawer withdraws the stacked plates and returns the follower, and means for releasing the latch of the follower from the drawer when the follower has been returned to initial position. 55
27. The combination of an addressing machine adapted to deliver individual plates forwardly and downwardly, means for moving the delivered plates rearwardly to stack them in a horizontal row beneath the addressing machine, and an inking ribbon mounted on two spools in the addressing machine, and means for guiding said ribbon to cause it to pass intermediately beneath said horizontal row of stacked plates. 60
28. The combination with an address printing machine having means for feeding plates and having an inking ribbon, and a separable sub-base having restacking means and having ribbon guides open toward the outside, whereby the ribbon may be so mounted in the address printing machine 65 that it may be passed beneath the sub-base and the address plates therein to a spool in the address printing machine. 70
29. The combination of an address printing machine having means for feeding individual plates, a base having means for stacking delivered plates, and having provision for the insertion of a drawer to remove such stacked plates, an inking ribbon mounted on two spools carried by the address printing machine, said ribbon being guided intermediately across a plate in printing position and thence downwardly and beneath the region adapted to be occupied by the drawer, thence upwardly to another spool mounted in the address printing machine. 75
30. The combination with an addressing machine having means for feeding and delivering individual address plates, of a separable base adapted to be mounted beneath the machine and receive the delivered plates and stack them in a horizontal row, and an inking ribbon carried by spools mounted in the addressing machine, there being guiding means for directing the ribbon intermediately across the address plate in printing position and thence beneath said plate in the addressing machine or beneath the restack in the separable base, as desired. 80

31. In an address printing machine, the combination with means for feeding plates along a bed and beneath an inking ribbon carried thereby, of an impression arm carrying a platen to act on said ribbon and address plate therebeneath, and a listing attachment comprising a bracket adapted to be secured to the bed and having a roller adapted to coact with a strip of paper overlying the ribbon, a clutch driving said roller, means for operating the impression arm and the clutch, and an adjustably positioned stop for limiting the effective stroke of the clutch operating mechanism in one direction only.
32. In an address printing machine adapted to receive, print from and discharge individual address plates, the combination with a supply magazine of means to engage the plates in such magazine and centralize them, holding them out of contact with the magazine walls adjacent the ends of the plate.
33. In an address printing machine, the combination with a magazine of address plates having projecting tongues adjacent to the opposite edges, and means in the magazine adapted to enter between said tongues to position said plates.
34. In an addressing machine, the combination with plates having projecting tongues adjacent two of the corners of the plate, a magazine adapted to house said plates and inclined members in the magazine adapted to engage between said tongues to automatically center the plates.
35. In an address printing machine, the combination with a bed and means for feeding plates along the same, of a platen adapted to coact with a plate in a certain position and also overhanging an adjacent portion of the bed, and a holding device mounted on such adjacent portion of the bed and having means for slidably carrying a removable printing member.
36. In an address printing machine, the combination with means for feeding plates, of a platen adapted to coact with one of the plates and also projecting beyond the end thereof, a holding device mounted to stand beneath such projecting portion of the platen and having upwardly extending undercut projections, and an inwardly flanged printing member slidably mounted on said projections.

In testimony whereof, I hereunto affix my signature.

CLIFTON CHISHOLM.
